FIG. 4.

UNITED STATES PATENT OFFICE.

JOSEPH DAVIDSON, OF EAST POINT, GEORGIA, ASSIGNOR OF ONE-HALF TO AMERICAN MACHINE & MANUFACTURING COMPANY, A CORPORATION OF NORTH CAROLINA.

MACHINE FOR FORMING OIL-CAKES.

1,250,147.

Specification of Letters Patent. Patented Dec. 18, 1917.

Application filed January 13, 1916. Serial No. 71,840.

To all whom it may concern:

Be it known that I, JOSEPH DAVIDSON, a citizen of the United States, and resident of East Point, county of Fulton, and State of Georgia, have invented an Improvement in Machines for Forming Oil-Cakes, of which the following is a specification.

The object of my invention is to provide a suitable machine for forming oil-cakes which may be effectively operated to produce cakes of uniform size and of approximately uniform weight and density, said operations being accomplished with a minimum requirement of care on the part of the attendant. My object is further to provide suitable means for mechanically delivering the meal or ground seed, from which the oil is to be extracted, to the mold box of the cake former in a condition and quantity which will enable uniform cakes to be molded, and this result to be accomplished notwithstanding irregularity in the homogeneity of the meal due to the presence of lumps therein.

With the above and other objects in view, the nature of which will be more fully understood from the description hereinafter, the invention consists in the novel combination of the parts as well as the specific construction of certain features thereof which enter into the organization of my improved oil-cake former, as hereinafter more fully described and defined in the claims.

Referring to the drawings:—Figure 1 is a side elevation of an oil-cake forming machine embodying my invention; Fig. 2 is an end elevation of the same; Fig. 3 is a longitudinal sectional elevation of my improved oil-cake forming machine with a portion of the operating means for the charge box broken away, and showing the machine in the act of filling the mold box with meal from the charge box; Fig. 4 is a transverse sectional elevation of my improved machine on line $x-x$ of Fig. 1; Fig. 5 is a longitudinal sectional elevation of the hydraulic means for operating the charge box, and Fig. 6 a section of the main valves.

My improved machine is essentially hydraulically operated and is what is known in the trade as a hydraulic former, and comprehends in an organized machine the association of two mechanisms, namely that employed for charging the forming mecha-

nism with meal, and the forming mechanism which compresses the meal into the cake. The function of the charging mechanism is to transfer the cooked meal from the cookers and spread it in an even layer of about two and one-half or three inches thick over the press cloth, which has been previously placed in the bottom of the meal tray or mold which forms a part of the forming mechanism, whereby each cake may be of substantially the same shape and weight and of a substantially uniform density when finished. The function of the forming mechanism is to press the molded meal, and in doing this the free ends of the press cloth are first brought up and over the meal placed in the tray or mold by the charging mechanism, and the meal thus held in place by the tray and head tree is subjected to hydraulic pressure, thereby producing a cake having the press cloth over the two faces and ends and packed sufficiently hard to remain firm at the uninclosed side edges until after the cakes are transferred and placed in the press (for pressing out the cotton seed oil), wherein the side edges become firmly supported by the steel sides of the press box. While my invention is not restricted as to any specific shape of cake, the preferred dimensions are thirty-four inches long, fourteen inches wide, and one and seven-eighth inches thick, including the inclosing cloth. Cakes so formed are usually transferred from the former to the press upon a suitable cake pan which prevents the cake from becoming broken in transit.

The charging mechanism and forming mechanism above referred to are suitably supported upon a common foundation and both mechanisms are so associated as to be under the control of a single operator by devices to be hereinafter described.

2 is the base of the machine and has secured upon it, adjacent to one end, the hydraulic cylinder 8 in which there is the vertically movable plunger 7, said plunger carrying at its upper end the meal tray 3 of the mold box mechanism. This tray 3 is of general rectangular form and provided with a longitudinal rectangular recess or chamber 6 in its upper part which is open at opposite ends. The tray 3 is adapted to have a vertical reciprocating mo-

tion under the control of the hydraulic cylinder and plunger, and is guided in its vertical movement and held against lateral swinging or displacement by suitable guiding means 5 formed partly on the tray and partly on the upright frames 4 and 4^a which are secured to the base 2. These frames may be of any suitable construction. The tray 3 may be provided on the bottom of its recessed upper part with a lining 3^a upon which the press cloth 31 may rest, as clearly shown in Fig. 3. The upper part of the recessed portion of the tray may be closed by the head tree 10 which is provided with laterally extending arms secured upon the longitudinal shaft 11 arranged to one side of the tray 3 and carried by the upright frame 4. The construction of this head tree 10 is such that it may swing about the axis 20 of the shaft 11 so as to be brought into cooperation with the vertically reciprocating tray in the act of compressing the meal cake, and which can be turned up out of the way during the period of charging the tray with 25 the meal and when removing the completed cake from the tray (see dotted lines, Fig. 4).

The means for operating the head tree will now be described:—Referring to Fig. 4, 18 is a latch which is hinged at 19 to suitable lugs on the head tree at the opposite side thereof to the shaft 11, and said latch has its lower end 18^a inwardly projecting so as to engage a cross bar or keeper 4^b on the upright frame 4^a, and in this manner 35 hold the head tree against shifting during the compression operation. The aforesaid lugs of the head tree are shaped to rest upon the top of the said frame 4^a, so that the position of the head tree is definitely fixed 40 when the parts are adjusted as indicated in Fig. 2. The upper end of the latch 18 is jointed to the link 16 which is extended across the head tree and hinged to a toggle plate 12 journaled upon the shaft 11, said 45 toggle plate connected to the piston rod 13 of the piston 14 working in the hydraulic cylinder 14^a. This cylinder is preferably pivoted on trunnions at 14^b in the upright frame 4, said pivotal arrangement being to 50 permit oscillation to suit the shifting of the piston rod under the rocking of the toggle plate 12. When the piston 14 is forced downward, the toggle plate 12 is rocked and the link 16 shifted to oscillate the latch 18 55 whereby it is released from the cross bar or keeper 4^b, said movement being permitted until the latch 18 is brought into contact with the end of the screw 20 carried in the head tree. During this action the spring 60 17, surrounding the link 16, is compressed against the slotted lug 10^a of the head tree. The power of this spring 17 may be adjusted by the adjusting nuts 16^a upon the said link. The function of spring 17 is to assist 65 in oscillating the latch 18 to cause it to en-

gage the keeper or bar 4^b when the head tree is brought into position to act as an abutment preliminary to the act of compressing the meal. In addition to the spring 17, a spring 15 may also be employed between 70 the top of the cylinder 14^a and a collar 13^a around the piston rod 13, the function of which is to return the piston 14 to the upper part of the cylinder when the hydraulic pressure is released from said cylinder, said action being assisted by the weight of the head tree while being lowered from the dotted line position into the solid line position, Fig. 4, preliminary to the compression operation. The spring 17 cooperates with 80 the spring 15 in bringing the parts to the condition indicated in Fig. 4, and the adjustability of spring 17 provides the spring devices as a whole with capacity for adjusting 85 their combined power.

The ends of the tray, normally open, are adapted to be closed during the charging of the tray and before the compression operation, and the manner of closing these ends is indicated in Figs. 1, 2 and 3. At the end 90 of the tray farthest removed from the charging mechanism is a swinging apron 26 which is secured to a rock shaft 27 and counterweighted at 28°, so that the normal tendency is for the apron to rise up out of the way 95 of the tray as indicated in Fig. 2, but which apron may be thrown down into closed position as indicated in Fig. 3 during the charging operation. The apron is made flat on the top and in alignment with the upper 100 guide surface 3^b of the tray, whereby the charge box 33 may be guided beyond the end of the tray, as will be understood by reference to Fig. 3. The operation of the rock shaft 27 to bring the swinging apron 105 26 into and out of operation will be described hereinafter. The other end of the tray is closed by the abutment 32^a of the sliding apron 32 which is adapted to transfer the charge box 33 with its contents from receiving position below the meal chute 38 (from the cookers) to the distributing position above the tray in the act of charging the latter (Fig. 3). The sliding apron 32 is moved from its position indicated in Fig. 110 1 to its position indicated in Fig. 3 by means of a plunger 40 working in a hydraulic cylinder 41, said plunger being connected with a downwardly projecting portion from the under side of the apron. The fluid pressure for the cylinder 41 is supplied by a pipe 42 under the control of a valve 44 to be hereinafter described. The sliding apron 32 is guided upon the main frame 2^a so as to reciprocate in a horizontal plane, and is moved backward to the position indicated in Fig. 1 by the action of the charging mechanism, as will be described hereinafter. After the tray has been closed at each end 115 and has been charged with the meal in the 120

manner illustrated in Fig. 3, and hereinafter described, the sliding apron 32 is moved back to the position indicated in Fig. 1, and the pivoted apron 26 is allowed to move upwardly (by means later to be described) as indicated in Fig. 2, and thereafter the ends of the press cloth are turned up over the meal charged in the tray so that the ends are closed against the escape of the meal.

10 The head tree 10 is then swung downwardly and latched as indicated in Fig. 4, said operation being caused by the weight of the head tree and controlled by the release of the fluid pressure from the cylinder 14^a, said release being permitted by the action of the hydraulic valve 22 under manipulation of the lever 23, and the speed of release of the fluid from the cylinder 14^a is regulated by a needle valve 22^c, in the pipe 22^d connecting the valve 22 with the said cylinder. The pressure fluid for the cylinder 14^a is delivered thereto and therefrom through this pipe 22^d having said needle valve 22^c, the said pipe making a liquid tight adjustable joint through the trunnion 14^b of said pivoted cylinder.

When the head tree is finally lowered and locked in position as indicated in Fig. 2, the fluid pressure is admitted to the hydraulic cylinder 8 through the valve 9 and the ports 8^a (Figs. 3 and 4) with the result that the plunger 7 is forced upwardly and carries with it the meal tray, producing compression of the meal in its confined condition within the meal tray and its inclosing press cloth. The valve 9 is operated by a stem 9^a, is normally moved to a closed position by the action of a spring 9^b and to an open position by means of the pivoted lever 40 fulcrumed at 21 and having its upper end in position to be actuated by the hooked end 18^a of the latch 18 (Fig. 4). In this manner it is seen that when the head tree is moved into operative position with the meal tray and locked in such position by the latch 18, said action automatically operates the valve 9 to provide pressure to the hydraulic cylinder 8 to produce proper compression of the meal. When the latch 18 is operated to 50 release the head tree after the compression, the spring 9^b of the valve 9 automatically moves the valve to its closed position and oscillates the lever 20 into a position by which it may, in the next operation, be actuated by the latch 18, as in the case above described. In this manner it is seen that the valve is automatic in its opening and closing, but indirectly this operation is controlled by the hand lever 23 which directly 55 controls the operation of the main valve 22 which in turn controls the cylinder 14^a and thereby the head tree.

I will now describe the general construction and arrangement of the two main valves 60 22 and 24 (Figs. 2 and 6):—24^a is the high

pressure fluid supply pipe, and 25^a is the exhaust or relief pipe, the same communicating with accumulator apparatus of any suitable character. The main valve 24, Fig. 2, which is operated by the lever 23, may be of 70 any suitable construction for intermittently admitting fluid under high pressure to the pipe 8^a, and normally delivering fluid to the pipe 22^a connecting with the valve 22 which controls the supply and discharge to the 75 head tree operating cylinder 14^a through pipe 22^d. The high pressure fluid from the pipe 8^a passes through the body of the check valve casing 8^d, and by the pipe 8^c is delivered to the valve chamber of the inlet valve 80 9 for supplying fluid under pressure to the cylinder 8, when said valve is opened, as before explained. The check valve 8^d below the ball valve is, by pipe 8^e, in communication with a port 8^b which leads to and opens 85 into the port 8^a extending into the chamber of the hydraulic cylinder 8. In this way when the high pressure is admitted by the main valve 24, said high pressure holds the check valve upon its seat, and under the 90 control of the valve 9 is admitted to the hydraulic cylinder 8. When the pressure in the cylinder 8 is to be relieved, the main valve 24 is operated by having its plunger 24^x depressed, said action shutting off the 95 supply of fluid at high pressure to the pipe 8^a, and putting said pipe in communication with the exhaust or relief pipe 25^a. This action permits the fluid pressure in the 100 hydraulic cylinder 8 to be relieved through the port 8^b, pipe 8^c, check valve 8^d, pipe 8^e, into the exhaust or relief pipe 25^a, thereby allowing the meal tray to descend into its original position. The main valve 24 is operated by the hand lever 23, the handle 23^a thereof being raised when applying pressure to the hydraulic cylinder 8, and depressed when relieving the said hydraulic cylinder of such pressure. The valve 22 which controls the 105 pressure to the oscillating cylinder 14^a is substantially the same as the main valve 24 though reversed, and operates substantially as follows:

When the valve plunger 22^x thereof is raised as shown in Fig. 2, the high pressure fluid passes by the pipe 22^a to the cylinder 14^a, and the exhaust pipe 22^b is shut off. When the plunger 22^x is depressed, the high pressure supply is shut off and the cylinder 14^a exhausts through the relief pipe 22^b and 115 through the main valve 24 into the relief pipe 25^a. As valve 22 would require that its plunger 22^x shall be depressed to relieve the pressure in the oscillating cylinder 14^a, it will follow that this is accomplished by lifting the handle end 23^a of the lever 23; and when the valve plunger 22^x is being shifted, the lever 23 will also raise the plunger 24^x of the valve 24 to close its exhaust and supply 120 fluid pressure to the pipe 8^a. 125 130

When the fluid pressure is relieved from the cylinder 14^a by the manipulation of the valve 22 through the raising of the handle end 23^a of the lever 23, the piston 14 is 5 gradually raised under the action of the spring 15 and the weight of the head tree and its connections, said head tree and connections swinging about the axis formed by the shaft 11. During this action, the latch 10 18 is held out of locking position by the gravity action of the said head tree modified by the spring 17 until the said head tree rests upon the top of the frame 4^a, 4^b, after which the further combined actions of the 15 springs 15 and 17 will oscillate the latch 18 whereby its hooked end 18^a passes under the keeper or bar 4^b and thereby locks the head tree in horizontal position, as shown in Fig. 2. The special operations which take place 20 in insuring this particular action involved in the lowering of the head tree and also in its return movement to elevated position, will be more fully described in the operation of the apparatus following the description 25 of the charging mechanism, now to be described.

I will now describe the charging mechanism used in combination with the forming mechanism hereinbefore described. The 30 cooked meal is delivered from the cookers (not shown) through the meal chute 38 and the discharge therefrom is controlled by the slide valve 39 (Fig. 3). The valve seat for valve 39 is upon the under side of 35 the bridge casting 38^a which is supported at its sides by the upright brackets 38^b extending from the main frame 2^a (Fig. 1); and the chute 38 is secured at its bottom to the bridge casting and at its top to the cookers 40 (not shown). This valve 39 is secured to the upper part of the brackets 38^a formed integral with the sliding apron 32 heretofore described, so that when the apron is moved forward by the action of the hydraulic plunger 40 and cylinder 41, the slide 45 valve 39 will shut off the delivery of the cooked meal or "meats" from the chute 38. The charging box 33 is normally resting upon the sliding apron and under the chute 50 38, but when this occurs the apron 32 is moved back as indicated in Fig. 1, and at a time when the forming mechanism is compressing the meal cake. In bringing the charge box 33 to said position, it is pulled 55 backward by the piston rod 34, by which it is shifted, said piston rod provided with a spring or cushion 37^b which is moved against the flange 32^a just as the charge box 33 passes over the apron and part way under 60 the slide valve 39; and a further movement of the piston rod moves the apron and its slide valve together with the charge box to the position indicated in Fig. 1, in which the meal is permitted to pass from the chute 65 into the charge box. When the charge box

33 is again moved forward to transfer its meal charge to the meal tray, the apron 32 and its slide valve 39 also move forward, the former to bring its end 32^a into contact with the meal tray (as before described) 70 and its valve 39 into shut off position to close the chute 38 (Fig. 3). This forward movement of the apron 32 is accomplished by the plunger 40 and cylinder 41 under control of valve 44 which controls the supply of fluid under pressure through pipe 42 to said cylinder 41; and when fluid pressure is supplied to cylinder 41 it is simultaneously supplied to the cylinder 35 by a branch of the same piping 42. The cylinder 35 is provided with a piston 36 on the end of the piston rod 34 connected with the charge box. This cylinder 35 is secured to the main frame 2^a and is supplied with fluid under pressure at its distant and forward ends by the respective pipes 42 and 43. The pressure in pipe 43 is the initial pressure in the supply pipe 24^a and its branch pipe 24^b connecting with the valve 44. When the valve 44 exhausts the distant end 80 of cylinder 35 by pipe 42, it also exhausts the cylinder 41, and at such time the initial pressure on the forward side of the piston 36 forces it back and brings the apron and charge box to the position shown in Fig. 1, 95 the spring buffer 37^b on piston rod 34 next to the charge box 33, insuring an easy initial movement to the sliding apron 32. To prevent jar at the completion of this backward movement, the piston and piston rod are received upon a bumper 37 having a spring 37^a and inclosed in a head or cap 35^a of the cylinder 35 (Fig. 5). As the operative area on the rear side of the piston 36 is in excess 100 of the forward side by the area of the piston rod, it is manifest that when the valve 44 supplies the pipe 42 with fluid at the initial pressure, the piston will be moved forward and with it the charge box; that also relieves the apron and this with its slide valve is 105 moved forwardly by the plunger 40 and cylinder 41.

As the charge box and apron are required to move under automatic control, suitable provision is made to insure proper timing of the operation of the valve 44 and this will now be described. The valve 44 is best shown in Fig. 3, and comprises the casing 44^a secured to the upright frame 44^b and the piston valve 45 sliding therein, said piston valve providing enlarged cylindrical portions 45^a which alternately seat in the casing to supply fluid pressure or exhaust relief to the pipes 42. The inlet port of the valve 44 connects with pipe 24^b and the exhaust port with pipe 25^b, as shown in Fig. 1. When the piston valve 45 is raised, fluid pressure is delivered to pipes 42, and when lowered said pipes are exhausted. This piston valve 45 is operated 115 120 125 130

by a lever 28 (Fig. 4), fulcrumed on the frame 44^a and counterweighted at 28^b near the handle 28^a to insure oscillation by gravity when released. Journaled to the 5 lever 28 is a lug 45^a through which the upper end of an extension from the piston valve 45 projects (Fig. 3) and between said lug and the upper end of said valve extension there is arranged a coil spring 45^b. By this connection 10 between the lever 28 and valve 45, a downward oscillation to the handle end of the lever by gravity will positively force the piston valve 45 down upon its seat to shut off the fluid pressure and relieve the cylinders 41 and 35 of pressure by the pipes 42; and a reverse manually produced movement of the lever 28 will shift the valve 45 to close the exhaust and supply fluid pressure to the pipes 42. When the weighted or 15 handle end of the lever 28 is lifted by the operator, the piston valve 45 is shifted to the open or pressure position and other end of the lever is locked in its depressed position by the pivoted latch 52 (Figs. 1 and 4), and 20 this insures the pressure being continued until said latch is released. This latch 52 is connected to one end of a rod 51, the other end of which is hinged to an arm 50 of a lever fulcrumed at 49 on 25 the main frame 2^a, said lever having its other or curved arm 48 in the path of a collar 47 adjustably secured upon a trip rod 46 secured to the charge box 33 so as to move with it, said collar depressing the arm 30 48 and tripping the latch 52 to release the lever 28 when the charge box has reached the limit of its charging travel. In this way the time of operation of the piston valve 45 is assured to cause relief or exhaust of the 35 pressure in the pipes 42 and insure a return of the charge box and apron to their initial position (Fig. 1). When the latch has been tripped as above stated the weighted end of the lever 28 descends by gravity and in doing so forces down the piston valve 45 to its 40 exhausting position. The particular function of the spring 45^b is here to insure the piston valve 45 positively seating in its exhausting position while permitting the lever 45 to move slightly more so that it may become locked by latch 52, said spring compensating for wear and lost motion of the latch pivot and other parts and yet insuring positive seating of the valve under all conditions. 50 In this way, the lever 28 has capacity for somewhat greater movement than would be required to fully throw the valve 45, but as gravity can only operate to compensate for lost motion when the valve is in exhausting 55 position, the spring is resorted to as a means to compensate for lost motion in the open or pressure supply position, and obviate necessity for very accurate relative movement of the lever. The normal tendency of the 60 apparatus is to throw the latch 52 into latch- 65

ing position by gravity and this may be increased by a weight 50^a applied to the arm 50, if so desired.

Aside from the function of operating valve 44, the lever 28 is arranged to operate the 70 rock shaft 27 for actuating the pivoted apron 26. The rock shaft 27 has upon its end an arm 30, which is connected by a link 29 with the lever 28 at a point on the opposite side of its fulcrum to which connection is made 75 with valve 44. By this means, it will be seen, the lifting of the lever 28 into locked position will simultaneously swing down the pivoted apron 26 at the same time that it puts the sliding apron 32 and charge box 80 into motion for charging the meal tray. It will further be seen, that while the lowering of the apron 26 is thus done manually so that it shall be in position for receiving the charge box (Fig. 3), its release to upward 85 position (Figs. 1 and 2) is insured automatically by the tripping of the latch 52 when the charge box has reached to the extreme of its movement. It will further be noted that the counterweight 28^b assists the 90 weight 28^a in shifting the lever 28 to operate the valve 44.

From the foregoing it will be observed that the operator is only required to lift the lever 28 into locked position, and the remaining operations of charging the meal tray and return of the parts to their initial positions (Fig. 1) are all done automatically, thereby making the machine easy of manipulation and operable by unskilled labor. 100

Referring more specifically to the charge box 33 itself, it will be seen that it is open at top and bottom and slightly tapering to permit easy fall of the meal by gravity as soon as the box passes from the apron 32, 105 over the meal tray 6, and the capacity of the "charge" of the box is proportioned so that it will insure complete filling of the tray by one reciprocation; and such excess of meal as remains in the box when it returns 110 to the sliding apron 32, will be used in the next "charge." Pivoted within the charge box is the packing vane 33^a which is free to take an inclined position between stops 33^b on the side of the box, the lower edge of the vane trailing backward to provide an inclined cam or packing surface. Referring to Fig. 3 and assuming that the box 33 is being moved to the left, it will be seen that the meal passing below the vane 33^a is positively pushed downward and packed into the tray. This vane also has a further and important function, namely, to prevent lumps in the meal producing furrows in the 115 surface of the meal in the tray and consequent production of defective meal cakes. Loose meal after being cooked or during cooking process, sometimes has a tendency to stick together and also to any iron or steel parts with which it comes into contact, 120 125 130

and this tendency occasionally presents itself when in the backward movement of the charging box, the edge, in skimming over the meats in the charged tray, comes in contact with a lump of meal (which has probably formed in the cookers), and carrying it along, causes a furrow to be formed in the meal in the tray. If the meal is slightly packed in the tray instead of being merely dropped in, the lump referred to would be scraped off by the edge of the charge box before it could do any damage. The vane 33^a acts to suitably pack the meal in the tray and in this way overcome the furrowing tendency of the lumps. If any lumps are in the charge box and are deposited in the tray during the outward or charging movement of the box, they would be broken up and packed down by the vane 33^a, and any small depressions which might occur to the rear of such lumps would be filled by the meal left in the forward end of the charge box as the box is returned. It is manifest that, as the vane 33^a does not reach to the rear of the box, such lumps as above mentioned might work down from the box into the tray, but in the return movement of the charge box and with the vane in its dotted position (Fig. 3), the lumps would be broken up and the meal packed down; and the slight furrow which might thus be produced, filled by the meal to the left of the vane. In practice, the outward movement of the charge box should preferably be sufficient to bring the bottom edge of the vane 33^a over or beyond the forward edge of the swinging apron 26, so that, both in the forward and return movements of the box, the vane will act efficiently over the entire body of meal in the meal tray. The use of this packing vane or cam surface insures the meal in the press cloth to be without holes or depressions and of approximately uniform density, with the result that the compressed cakes are homogeneous and well suited for use in the press.

Assuming that the meal tray has been properly filled with the meal, the operator brings both ends of the press cloth up over the meats in the tray and then raises lever 23, operating both valves 22 and 24. Valve 24 closes the exhaust and admits the fluid pressure from the accumulator or other source, and valve 22 closes against fluid pressure and opens to exhaust to relieve the piston 14. This permits the spring 15 to move the piston upward to swing down the head tree 10. During this operation, the fluid pressure is up to the valve 9 but not permitted to enter cylinder 8. The head tree swings down about its pivotal shaft 11, first by the action of the spring 15 and then by its own weight as it nears the limit of its downward movement and comes to rest in position above the open top of the meal

tray, being supported in said position by the shaft 11 on one side, and the top of the frame 4^a on the other (Fig. 4). As the toggle plate 12 is free to oscillate on shaft 11 and is connected both with link 16 and piston 14, and as the upward movement of the piston is regulated by the speed of exhaust or relief of pressure permitted by the needle valve 22^a, the gradually increasing force of the weight of the head tree, due to the increasing leverage as it descends, is retarded to some extent by the spring 17 being compressed, the result of which action is to swing the latch outward at the lower or locking end. This action continues until stopped by the set-screw 20 contacting with the latch 18. As the head tree is further lowered to its final position (Fig. 4), the latch will have cleared the keeper or bar 4^b, and as the springs 15 and 17 will then be relieved of the weight of the head tree they will jointly produce a final shifting of the link 16 and latch to cause the latter to swing into locking engagement with the bar 4^b, as shown in Figs. 2 and 4. The head tree is now locked firmly in position in contact with meal in the tray and, as shown in Fig. 4, will have slightly compressed it as an initial consequence of the head tree positioning itself for the heavy compression action to follow. When the latch 18 is moved into locking position, it trips the lever 20 and opens the valve 9 to admit fluid pressure to the cylinder 8, with the result that the plunger 7 and tray 3 are forced upward upon the head tree and fully compress the meal cake. The operator has, during these operations, held the lever 23 in his hand and now when he feels the very slight vibration due to the completion of the action of compression, he lowers the lever to shift the valve 22 and 24, exhausting from valve 24 and supplying pressure from valve 22 to the cylinder 14^a. The result is, that the cylinder 8 exhausts through check valve 8^b and valve 24 and lowers the meal tray and the piston 14 moves down under the fluid pressure with compression of springs 15 and 17 and oscillation of the latch 18 outward at the bottom to release the head tree. As the operation of the piston 14 continues, the latch 18 contacts with the set screw 20, and then the head tree 10 ascends with the latch and swings about its pivotal axis on shaft 11 to the dotted position, Fig. 4. At this time the collar 13^a on the piston 14 will contact with the top of the cylinder 14^a and arrest further movement of the parts. It will be evident that, in such operation, as the head tree ascends its weight is balanced on shaft 11 to a gradually increasing extent, until at some point, near its extreme upward movement, the decreasing gravity action due to its weight is over-balanced by the force of the spring 17 to operate the 130

latch 18; and at the same time the decreasing force required to raise the head tree is compensated for by the increasing force of the spring 15 during its compression and 5 until arrested by the collar 13^a aforesaid. When this operation has been completed the attendant takes the completely formed cake from the meal tray on a cake pan, by which it is transferred to the box of the press in 10 the usual manner.

It will be seen from the foregoing description that the operator is not required to be skilful inasmuch as the forming mechanism is automatic in operation except for 15 the single lever operation for opening and closing the main valves.

It will be noted that when the fluid pressure is relieved by lowering the lever 28, the hydraulic cylinder 8 is exhausted, not only 20 through the check valve 8^a but also initially by the valve 9, and this continues until the latch 18 has released the lever 20 and permitted the valve 9 to close, after which, the relief is completed by the check valve alone.

25 In this way, there is more rapid relief of the cylinder 8 at the start, and this is desirable as it more quickly lowers the meal tray and to an extent sufficient to permit free release of the head tree by the time it 30 has been unlatched by the latch 18; after which, the lowering of the meal tray and raising of the head tree take place simultaneously.

The great simplicity of operation of my 35 improved machine, in so far as hand manipulations are concerned, will be apparent when we state the sequence of such manipulations, keeping in mind that all other operations of the machine as a whole are purely 40 automatic. They are:—(1) placing the press cloth in the meal tray; (2) raising with the left hand the operating lever 28; (3) folding the press cloth over the meal in the tray; (4) raising and lowering with 45 the right hand the lever 23. The operator has, therefore, only been required to perform four manipulations and two of these are simple adjustments of the press cloth.

An attendant removes the compressed or 50 formed cake from the tray and conveys it to the press and the operator proceeds as before. In machines heretofore in use, there were required several more manipulations than the above, thus making the forming of 55 the cakes in an oil mill a very slow and unsatisfactory process. By reason of the automatic action in my machine, it is possible for me to form the cakes hydraulically with better and quicker results, not only than 60 are produced by hydraulic formers heretofore in use, but also with better satisfaction than has heretofore been attained with steam formers, and at the same time eliminating the inherent defects incident to the use of 65 steam in this art.

It will now be apparent that I have devised a novel and useful construction which embodies the features of advantage enumerated as desirable, and while I have in the present instance shown and described the 70 preferred embodiment thereof which has been found in practice to give satisfactory and reliable results, it is to be understood that I do not restrict myself to the details, as the same are susceptible of modification in 75 various particulars without departing from the spirit or scope of the invention.

Having now described my invention, what I claim as new and desire to secure by Letters Patent, is:—

1. In a cake former, a meal tray in which the cake is to be formed, combined with a sliding apron in alinement with the meal tray, a meal chute, a valve device for controlling the discharge from the meal chute secured to and moving with the sliding apron, a charging device for receiving the meal from the chute and delivering it to the meal tray, and suitable means for reciprocating the charging means and apron. 80

2. In a cake former, a meal tray in which the cake is to be formed, combined with a sliding apron in alinement with the meal tray, a meal chute, a valve device for controlling the discharge from the meal chute secured to and moving with the sliding apron, a charging device for receiving the meal from the chute and delivering it to the meal tray, suitable means for reciprocating the charging means and also move the apron and valve device in one direction away from the meal tray for opening the meal chute, and separate means for moving the apron in the other direction toward the meal tray. 95

3. In a cake former, the combination of a meal tray, a sliding apron in alinement with the meal tray and having an end forming a closure of the meal tray when the apron is moved toward it, power devices for moving the sliding apron toward the meal tray, a meal chute having its discharging end arranged above the sliding apron, a reciprocating charge box adapted to slide over the surface of the apron and meal tray and adapted to be brought into alinement beneath the discharging end of the meal chute, power devices for reciprocating the charge box in both directions and also moving the sliding apron away from the meal tray, and suitable means for controlling the discharge 105 of the meal from the chute into the charge box. 110

4. In a cake former, the combination of a meal tray, a sliding apron in alinement with the meal tray and adapted to be moved to 125 temporarily close the end thereof, a meal chute, a valve device carried by the apron for controlling the discharge of meal from the chute, a reciprocating charge box adapted to slide over the apron and meal tray and 130

also under the meal chute, and means for shifting the apron and valve device when bringing the charge box under the chute whereby the meal will be discharged from the chute into the charge box.

5. In a cake former, the combination of a meal tray, a sliding apron in alinement with the meal tray and adapted to be moved to temporarily close the end thereof, a meal chute, a valve device carried by the apron for controlling the discharge of meal from the chute, a reciprocating charge box adapted to slide over the apron and meal tray and also under the meal chute, means for shifting the apron and valve device when bringing the charge box under the chute whereby the meal will be discharged from the chute into the charge box, and separate means for moving the sliding apron and the valve devices into position for shutting off the escape of meal from the chute and moving the apron toward the meal tray when the charge box is being moved toward the meal tray.

6. In a cake former, the combination of a meal tray, a sliding apron in alinement with the meal tray and adapted to be moved to temporarily close the end thereof, a meal chute, a valve device carried by the apron for controlling the discharge of meal from the chute, a reciprocating charge box adapted to slide over the apron and meal tray and also under the meal chute, means for shifting the apron and valve device when bringing the charge box under the chute whereby the meal will be discharged from the chute into the charge box, separate means for moving the sliding apron and the valve devices into position for shutting off the escape of meal from the chute and moving the apron toward the meal tray when the charge box is being moved toward the meal tray, and manually controlled valve devices for simultaneously controlling the operation of the means for moving the apron and its valve device and also the charge box toward the meal tray.

7. In a cake former, the combination of a meal tray, a sliding apron in alinement with the meal tray and adapted to be moved to temporarily close the end thereof, a meal chute, a valve device carried by the apron for controlling the discharge of meal from the chute, a reciprocating charge box adapted to slide over the apron and meal tray and also under the meal chute, means for shifting the apron and valve device when bringing the charge box under the chute whereby the meal will be discharged from the chute into the charge box, separate means for moving the sliding apron and the valve devices into position for shutting off the escape of meal from the chute and moving the apron toward the meal tray, manually controlled valve devices for simultaneously controlling the operation of the means for mov-

ing the apron and its valve device and also the charge box toward the meal tray, and automatic devices independent of hand control for returning the charge box, the apron, and the valve device to their original positions after charging the meal tray. 70

8. In a cake former, the combination of a meal tray, a meal chute, a charge box for transferring the meal from the meal chute to the tray, a valve separate from the charge box for closing the meal chute except when the charge box is under it, power devices for reciprocating the charge box, manually controlled means for timing the operation of the power devices, and means of less power than and independent of the power devices for operating the valve and whose time of action in operating the valve is only a portion of the time of action of the charge box but controlled by the power devices 85 which operate the charge box.

9. In a cake former, the combination of a meal tray, a meal chute, a reciprocating charge box for transferring meal from the chute to the tray, an operating cylinder, a piston rod for said cylinder connected with the charge box and having a piston within the cylinder, means for delivering continuously acting pressure to one end of the cylinder for moving the piston backward to return the charge box from the meal tray to a position under the meal chute, pipes for supplying pressure to the opposite end of the cylinder to push the piston forward for moving the charge box from the meal chute to the meal tray, and hand controlled valve devices for supplying pressure to the pipes or relieving them of pressure, whereby the piston is moved forward against the continuously acting pressure on its other side or has its pressure on its rear end relieved to enable the continuously acting pressure to exert itself to move the piston backward. 95 100 105

10. In a cake former, the combination of a meal tray, a meal chute, a reciprocating charge box for transferring meal from the chute to the tray, an operating cylinder, a piston rod for said cylinder connected with the charge box and continuously acting having a piston within the cylinder, a pipe for delivering a fluid pressure in the cylinder to one side of the piston for moving the piston backward to return the charge box from the meal tray to a position under the meal chute, pipes for supplying pressure to the opposite side of the piston said pressure delivered to the rear end of the cylinder to push the piston forward for moving the charge box from the meal chute to the meal tray, hand controlled valve devices for supplying pressure to the pipes or relieving them of operative pressure, whereby the piston is acted upon on one side and moved forward against the continuously acting pressure on its other side or has its pressure 115 120 125 130

on its rear end relieved to enable the continuously acting pressure to exert itself to move the piston backward said valve devices independent of the pipe for delivering the 5 continuously acting pressure, locking means to hold the valve devices in position to supply pressure to the pipes, and automatic means controlled by the movement of the piston rod for operating the locking device 10 to release the valve whereby it may shift and relieve the pressure in the pipe automatically after the piston has moved forward a predetermined distance.

11. In a cake former, the combination of 15 a meal tray, a meal chute, a reciprocating charge box for transferring meal from the chute to the tray, an operating cylinder, a piston rod for said cylinder connected with the charge box and having a piston within 20 the cylinder, means for continuously delivering a fluid pressure in the cylinder to one side of the piston for moving the piston backward to return the charge box from the meal tray to a position under the meal chute 25 said pressure delivered to the forward end of the cylinder, pipes for supplying pressure to the opposite end of the cylinder to push the piston forward for moving the charge box from the meal chute to the meal tray, 30 hand controlled valve devices for supplying pressure to the pipes or relieving them of pressure, whereby the piston is moved forward against the continuously acting pressure or has its pressure on its rear end relieved to enable the maintained pressure on 35 the other end to exert itself to move the piston backward, and a mechanical buffer device arranged within the rear end of the cylinder and adapted to take the thrust of 40 the piston and piston rod under the action of the continuously acting pressure to bring said parts to rest without shock.

12. In a cake former, the combination of 45 a meal tray, a meal chute, a sliding apron having a valve to control the chute, a reciprocating charge box adapted to slide over the apron and meal tray, two hydraulic motors for respectively moving the sliding apron and charge box in one and the same 50 direction, and means whereby the motor which moves the charge box shall cause the sliding apron to be moved in the opposite direction at a time commensurate with the final return movement of the charge box.

55 13. In a cake former, the combination of a meal tray, a sliding apron, a reciprocating charge box adapted to move over the apron and meal tray, means to charge the charge box with meal when over the apron, hand 60 controlled power devices for moving the apron and charge box toward the meal tray, and automatically operated means for causing the charge box and apron to be moved in the reverse direction.

65 14. In a cake former, the combination of

a meal tray, a sliding apron, a reciprocating charge box adapted to move over the apron and meal tray, means to charge the charge box with meal when over the apron, hand controlled power devices for moving the 70 apron and charge box toward the meal tray, automatically operated means for causing the charge box and apron to be moved in the reverse direction, and automatically operating means for controlling the time of reversal of movement of the charge box whereby said charge box has its movement reversed after completely passing over the meal tray.

75 15. In a cake former, the combination of a meal tray, a reciprocating charge box 80 adapted to be moved over the meal tray for charging it, a fluid pressure motor for moving the charge box over the meal tray, a hand controlled valve for admitting fluid pressure to the motor, locking means for 85 holding the valve in its position for supplying fluid pressure, means for causing the valve to shut off the fluid pressure when released and relieve the pressure from the motor, automatic devices for controlling the 90 locking device to release the valve when the charge box has moved over the meal tray, and means coöperating with the fluid pressure motor for returning the charge box to its original position from above the meal 95 tray when the valve is automatically unlocked.

16. In a cake former, the combination of a meal tray, a reciprocating charge box 100 adapted to be moved over the meal tray for charging it, a fluid pressure motor for moving the charge box over the meal tray, a hand controlled valve for admitting fluid pressure to the motor, locking means for holding the valve in its position for supplying fluid 105 pressure, means for causing the valve to shut off the fluid pressure when released and relieve the pressure from the motor, automatic devices for controlling the locking device to release the valve when the charge box has 110 moved over the meal tray, and means coöperating with the fluid pressure motor for returning the charge box to its original position from above the meal tray when the valve is automatically unlocked said means 115 consisting of devices independent of the valve for supplying a constant fluid pressure to the motor to reverse its operation automatically when the valve is moved to exhausting or relief position.

120 17. In a cake former, a meal tray, combined with a charge box, a fluid pressure motor to reciprocate the charge box, a valve for alternately supplying fluid pressure to the motor and relieving the pressure therefrom having a reciprocating part, a pivoted hand lever manually movable in one direction for operating the valve to supply fluid pressure, means for automatically moving the lever in the other direction to operate 125 130

- the valve to shut off fluid pressure and move it into exhaust position, a connection including a spring between the hand lever and the movable part of the valve whereby the movable part of the valve is moved positively into exhaust position by the hand lever and under spring action in the other direction to supply fluid pressure, a latch to lock the lever in position when it has been shifted to 5 move the movable part of the valve under the spring action, and means to release the latch controlled by the movement of the charge box whereby the movable part of the valve may be automatically shifted after 10 15 the charge box has been given a predetermined extent of movement to relieve the fluid pressure from the motor.

18. In a cake former, the combination of a meal tray, a charge box slideable over the 20 meal tray and having its top and bottom open, means to reciprocate the charge box, and a swinging vane pivoted within the charge box and extending transversely across the same and free to swing below its 25 pivot into an oblique position to provide a cam surface for forcing the meal downward into the meal tray.

19. In a cake former, the combination of a meal tray, a charge box slideable over the 30 meal tray and having its top and bottom open, means to reciprocate the charge box, and a swinging vane pivoted within the charge box and extending transversely across the same and free to swing below its 35 pivot into an oblique position to provide a cam surface for forcing the meal downward into the meal tray, said vane being arranged near the lower part of the charge box and capable of swinging into an oblique 40 position upon the opposite sides of the axis of oscillation whereby it may exert its downward packing action when the charge box is moved in either direction.

20. In a cake former, the combination of 45 a meal tray, a main frame, a bridge structure secured to and extending over the main frame and at a higher elevation than the meal tray, a meal chute connected with the top of the bridge and arranged to discharge 50 through the same, a charge box, means to reciprocate the charge box from within the bridge beneath the meal chute to a position over the meal tray, a suitable valve device for controlling the discharge of meal 55 from the chute into the charge box, and means for reciprocating the valve device a less distance than the movement of the charge box.

21. In a cake former, a main frame, combined with forming mechanism consisting of a meal tray, means to reciprocate the meal tray, a pivoted head tree adapted to cooperate with the meal tray in forming the cake, a latch pivoted to the head tree and 60 engaging the main frame for temporarily 65

locking the head tree in lowered position, a link connected with the latch, a spring between the link and the head tree tending to resist the gravity action of the head tree, a suitable stop to limit the extent of movement of the latch when moved to the unlatching position, a fluid pressure motor for operating link for raising and lowering the head tree, connecting means between the fluid pressure motor and the link, a valve 70 device for controlling the supply of fluid pressure to the fluid pressure motor, and a hand controlled means for operating the said valve.

22. In a cake former, a main frame, combined with forming mechanism consisting of a meal tray, means to reciprocate the meal tray, a pivoted head tree adapted to cooperate with the meal tray in forming the cake, a latch pivoted to the head tree and 80 engaging the main frame for temporarily locking the head tree in lowered position, a link connected with the latch, a spring between the link and the head tree tending to resist the gravity action of the head tree, 85 a suitable stop to limit the extent of movement of the latch when moved to the unlatching position, a pivoted fluid pressure motor having a reciprocable piston for operating link for raising and lowering the 90 head tree, a spring around the piston rod to raise the piston, connecting means between the fluid pressure motor and the link consisting of a toggle plate journaled adjacent to the pivotal axis of the head tree and 95 connected both to the link and to the free end of the piston, a valve device for controlling the supply of fluid pressure to the fluid pressure motor, and a hand controlled means for operating the said valve, whereby the 100 application of fluid pressure to the motor will first cause the compression of the spring on the link to unlatch the head tree and then cause the head tree to swing upward about its pivotal axis.

23. In a cake former, the combination of a main frame, a meal tray, power means to reciprocate the tray vertically, a head tree pivotally supported on the main frame and adapted to swing down into cooperation with the meal tray, locking means for locking the head tree to the main frame when in lowered position, a fluid pressure motor for operating the locking means and head tree, a source of fluid pressure, a main valve for controlling the fluid pressure to and from the fluid pressure motor, hand operable means for controlling the main valve, and an auxiliary adjustable needle valve to control the rate of discharge of the fluid pressure from the fluid pressure motor when the main valve is operated to release the pressure when lowering the head tree.

24. In a cake former, the combination of a main frame, a reciprocating meal tray, a 110 115 120 125 130

pivoted head tree hinged upon the main frame at one side of the meal tray and adapted to be supported by the main frame at the opposite side of the meal tray when 5 in lowered position, a latch carried by the head tree for locking it to the main frame when lowered, a motor having a piston for operating the head tree, a connection between the piston and the latch whereby the 10 latch is first operated by the motor to unlock the head tree and then raised with the head tree by the power of the motor, and a spring interposed between the head tree and the connection and opposing the motor action 15 for insuring the operation of the latch independently of the operation of the head tree.

25. In a cake former, the combination of a main frame, a reciprocating meal tray, a pivoted head tree hinged upon the main 20 frame at one side of the meal tray and adapted to be supported by the main frame at the opposite side of the meal tray when in lowered position, a latch carried by the head tree for locking it to the main frame 25 when lowered, a motor having a piston for operating the head tree, a connection between the piston and the latch whereby the latch is first operated by the motor to unlock the head tree and then raised with the head 30 tree by the power of the motor, a spring interposed between the head tree and the connection and opposing the motor action for insuring the operation of the latch independently of the operation of the head tree, 35 and a second spring independent of the head tree but opposing the motor action in raising the head tree and compensating for the varying leverage of the head tree as it is being raised.

40 26. In a cake former, the combination of a main frame, a reciprocating meal tray, a head tree adapted to coöperate with the meal tray hinged to the main frame at one side of said meal tray, a pressure motor having a 45 piston, and a spring connection between the piston and the head tree for raising and lowering the head tree.

27. In a cake former, the combination of a main frame, a reciprocating meal tray, a head tree adapted to coöperate with the meal 50 tray hinged to the main frame at one side of said meal tray, a pressure motor having a piston, a spring connection between the piston and the head tree for raising and lowering the head tree, and means to limit the extent of compression of the spring.

28. In a cake former, the combination of a main frame, a reciprocating meal tray, a head tree adapted to coöperate with the meal 55 tray hinged to the main frame at one side of said meal tray, a pressure motor having a piston, a spring connection between the piston and the head tree for raising and lowering the head tree, a second spring opposing 65 the action of the motor in raising the head

tree and for storing power for lowering the head tree when the pressure of the motor is released, and means for controlling the pressure supplied to the motor.

29. In a cake former, the combination of 70 a main frame, a reciprocating meal tray, a hinged head tree adapted to be supported by the main frame when fully lowered, a motor device, a yielding connection between the motor device and the head tree for oscillating the latter between its upper and lower positions, a latch for locking the head tree in its lowered position, and means whereby the weight of the head tree in descending normally holds the latch out of locking position until the said head tree has come to rest. 80

30. In a cake former, the combination of a main frame, a reciprocating meal tray, a head tree hinged to the main frame and adapted to swing into position above the 85 tray, a latch hinged to the head tree and adapted to lock the same to the main frame when fully lowered, means to limit the extent of movement of the latch, an oscillating motor cylinder and a piston therefor, 90 a rocking toggle frame, a connection between the toggle frame and the piston, a spring to oppose the piston action in oscillating the toggle frame, a link between the toggle frame and the latch, a spring between 95 the link and the head tree, and means to control the supply of pressure to the motor cylinder.

31. In a cake former, the combination of 100 a main frame, a vertically movable meal tray, a pressure motor for raising and lowering the tray, valve devices for controlling the pressure supplied to the motor, a movable head tree adapted to be moved into and out of relation with the meal tray, 105 means for operating the head tree, automatic means actuated by the head tree and its operating mechanism for operating the valve devices to supply pressure to the motor when the head tree is in lowered position. 110

32. In a cake former, the combination of a main frame, a vertically movable meal tray, a pressure motor for raising and lowering the tray, valve devices for controlling the pressure supplied to the motor, a movable head tree adapted to be moved into and out of relation with the meal tray, means for operating the head tree, automatic means actuated by the head tree and its operating mechanism for operating the valve devices 115 to supply pressure to the motor when the head tree is in lowered position, and manually controlled means for relieving the pressure from the pressure motor.

33. In a cake former, the combination of 120 a main frame, a vertically movable meal tray, a pressure motor to reciprocate the meal tray, a movable head tree adapted to be lowered into operative relation with the meal tray, power devices for raising and 130

lowering the head tree, a latch for locking the head tree in its lowered position, a source of pressure, a valve device for controlling the pressure supplied to the pressure motor, 5 means actuated by the latch in the act of locking the head tree for opening the valve to permit pressure to the pressure motor whereby the meal tray is forcibly raised, and separate means for relieving the pressure of the pressure motor.

34. In a cake former, the combination of a main frame, a vertically movable meal tray, a pressure motor to reciprocate the meal tray, a movable head tree adapted to 15 be lowered into operative relation with the meal tray, power devices for raising and lowering the head tree, a latch for locking the head tree in its lowered position, a source of pressure, a valve device for controlling the pressure supplied to the pressure motor, means actuated by the latch in the act of locking the head tree for opening the valve to permit pressure to the pressure motor whereby the meal tray is forcibly raised, and separate manually controlled 25 means for relieving the pressure of the pressure motor and for also operating the latch and controlling the power devices for raising the head tree.

35. In a cake former, the combination of a reciprocating meal tray, a fluid pressure motor for reciprocating the tray, an automatic valve device for supplying fluid pressure to the fluid pressure motor, a pivoted 35 head tree, a fluid pressure motor for operating the head tree, connections between the fluid pressure motor and the head tree also adapted to operate the automatic valve for supplying pressure to the fluid pressure 40 motor operating the meal tray when the head tree is fully lowered, a source of fluid pressure, and manually controlled valves for controlling the fluid pressure of the fluid pressure motor for operating the head 45 tree and for exhausting the fluid pressure from the fluid pressure motor for operating the meal tray.

36. In a cake former, the combination of a reciprocating meal tray, a fluid pressure 50 motor for reciprocating the tray, an automatic valve device for supplying fluid pressure to the fluid pressure motor, a pivoted head tree, a fluid pressure motor for operating the head tree, connections between the 55 fluid pressure motor and the head tree also adapted to operate the automatic valve for supplying pressure to the fluid pressure motor operating the meal tray when the head tree is fully lowered, a source of fluid 60 pressure, manually controlled valves for controlling the fluid pressure of the fluid pressure motor for operating the head tree and for exhausting the fluid pressure from the fluid pressure motor for operating the 65 meal tray, an exhaust port from the fluid

pressure motor for operating the meal tray and acting as a by-pass about the automatic valve, and a check valve arranged in said exhaust port.

37. In a cake former, the combination of 70 a meal tray, a head tree, separate fluid pressure motors to operate the head tree and the meal tray, a source of fluid pressure, a main valve for controlling the supply and exhaust of the fluid pressure motor for the head tree, a second main valve for supplying and exhausting fluid pressure in respect to the fluid pressure motor for the meal tray, a single manually controlled part for alternately operating the two main valves, whereby fluid pressure is supplied to or exhausted from the two pressure motors alternately, and a separate automatic 80 valve device controlled by the action of the fluid pressure motor for operating the head tree for controlling the time of admission of the fluid pressure to the fluid pressure motor which operates the meal tray.

38. In a cake former, the combination of 90 a meal tray, a head tree, separate fluid pressure motors to operate the head tree and the meal tray, a source of fluid pressure, a main valve for controlling the supply and exhaust of the fluid pressure motor for the head tree, a second main valve for supplying and exhausting fluid pressure in respect to the fluid pressure motor for the meal tray, a single manually controlled part for alternately operating the two main valves, whereby fluid pressure is supplied to or exhausted from the two pressure motors alternately, a separate automatic valve device controlled by the action of the fluid pressure motor for operating the head tree for controlling the time of admission of the fluid pressure to 100 the fluid pressure motor which operates the meal tray, and a check valve release acting as a by-pass about the automatic valve for the fluid pressure motor for the meal tray, whereby the said valve may close before the 110 fluid pressure has been wholly exhausted.

39. In a cake former, the combination of a meal tray, a plunger for raising and lowering the meal tray, a hydraulic cylinder for the plunger, a fluid pressure port for the cylinder, an automatic valve to normally close the port, a head tree, a movable means for locking the head tree in operative position, and connecting means between the latch and the automatic valve whereby the 115 operation of the latch in locking the head tree opens the valve.

40. In a cake former, the combination of a meal tray, a plunger for raising and lowering the meal tray, a hydraulic cylinder for the plunger, a fluid pressure port for the cylinder, an automatic valve to normally close the port, a head tree, a movable means for locking the head tree in operative position, connecting means between the latch 125 130

and the automatic valve whereby the operation of the latch in locking the head tree opens the valve, a manually controlled main valve for controlling pressure supplied to the automatic valve, and a by-pass from the hydraulic cylinder about the automatic valve and having a check valve for exhausting the said cylinder under the control of the main valve independently of the automatic valve.

41. In a cake former, the combination of a main frame, a vertically movable meal tray, a hinged head tree, means for moving the head tree, a latch for locking the head tree to the main frame in lowered position, a hydraulic cylinder, a plunger for the cylinder connecting with the meal tray, an automatic valve for controlling the supply of fluid pressure to the hydraulic cylinder, a spring to normally close the valve, and a lever pivoted to the main frame having a part connected with the automatic valve and another part adapted to be moved by the

latch whereby the locking of the head tree automatically admits pressure to the hydraulic cylinder.

42. In a cake former, the combination of a meal tray, a pivoted apron at one end of the meal tray counterweighted to normally move out of operative position, charging devices for delivering meal to the tray, a manually operated part for putting the charging devices into operation and also for lowering the pivoted apron into operative position with the meal tray, and automatic means under the control of the charging mechanism for releasing the pivoted apron, whereby it will automatically move out of operative position when the meal tray has been charged with meal.

In testimony of which invention, I hereunto set my hand.

JOSEPH DAVIDSON.
